Term of patent 14 years

(Cl. D74—2)

FIG.1

FIG.2

FIG.3

FIG.4

FIGURE 1 is a front perspective view of a clip for writing instrument, showing our new design; parts of a writing instrument being shown in broken lines for illustrative purposes;

FIGURE 2 is a front elevational view thereof;

FIGURE 3 is a side elevational view thereof; and

FIGURE 4 is a top plan view thereof.

The essential features of our design shown herein in solid lines reside in a clip of uniform width having vertical fluting on the upper angled portion thereof in combination with a series of substantially horizontal scribing at the bottom of the fluting, all as shown.

We claim:

The ornamental design for a clip for writing instrument, as shown and described.
